TERMINAL

Myron F. Whitney, Anderson, Ind., assignor to
 General Motors Corporation, Detroit, Mich.,
 a corporation of Delaware

Application December 13, 1935, Serial No. 54,175

5 Claims. (Cl. 173—311)

This invention relates to terminals and more particularly to terminals to be mounted and insulated on the frame of a generator.

The terminals heretofore employed, particularly in connection with generators are ordinarily of the type employing a threaded stud having a shoulder against which is placed a plain washer and covered with a body of non-conducting material. The body is molded about the washer and the stud so that a portion of the body will fit into a suitable aperture provided by the frame of the generator and insulate the stud and washer from the frame when the terminal is secured on the frame. Such a terminal is objectionable because when the terminal thus constructed is assembled with the frame and the clamping means drawn down tight, the washer will bend and cause a fracture of the non-conducting material surrounding it, thus causing short or open circuits.

An object of the present invention is to provide a design and an arrangement of a threaded member and a body of non-conducting material, which are combined into a unitary structure, whereby the body of non-conducting material will withstand all pressures exerted by clamping means to secure the unitary structure to a support without in any way injuring or fracturing the body, thus preventing short or open circuits.

Another object of the present invention is to produce a terminal of simple, compact and inexpensive construction.

Further objects and advantages of the present invention will be apparent from the following description, reference being had to the accompanying drawing wherein a preferred embodiment of the present invention is clearly shown.

In the drawing:

Fig. 1 is a fragmentary sectional view of a support showing a terminal member embodying the present invention assembled thereto.

Fig. 2 is a sectional view taken on the line 2—2 of Fig. 1.

Fig. 3 is an enlarged side view of one of the elements of the terminal member.

Fig. 4 is an enlarged side view of the whole terminal member.

Figs. 5 and 6 are sectional views taken on the lines 5—5 and 6—6 of Figs. 1 and 4 respectively.

Referring to the drawing, 20 designates a stud provided with a threaded end 21, a conical or tapered head 22 and a boss 23 extending from the face of the head 22. The boss is provided with a slot 24 to receive a bared end of a conductor wire 25 which is soldered to the boss 23.

to provide a good electrical connection between the wire and the boss. A body of suitable non-conducting material, preferably molded about the stud, is fixed to the stud to form a unitary terminal assembly 26. The molded body of non-conducting material includes an enlarged portion or flange 27 and a reduced portion 28. This reduced portion is provided with flats 29. It will be noted that the flange 27 substantially encloses the conical head 22, while the reduced portion 28 extends a part way up the threaded end 21 of the stud.

The terminal assembly 26 is adapted to be mounted to a suitable support 30, for example, the frame of a generator. This support is provided with an opening 31 therethrough, the opening being provided with flats 32. In assembling the terminal 26, the terminal is placed upon the support with the flats 29 of the reduced portion 28 registering with corresponding flats 32 of the opening. In other words the contour of the reduced portion 28 is substantially the same as the contour of the walls of the opening 31. Thus when the terminal 26 is assembled to the support the terminal is prevented from rotating relative to the support. It is to be understood that the contour of the reduced portion 28 and the opening 31 of any other shape may be employed which will provide the non-rotative relation between the terminal 26 and the support 30.

When the terminal 26 is assembled upon the support, the threaded end of the stud 21 will protrude through the opening 31. An insulating washer 33 and metallic washers 34 are placed over the threaded end 21. A clamping member or nut 35 is threaded on the end 21 to hold the terminal assembly 26 to the support and cause the inner surface 38 of the flange 27 to bear against the under side of the support 30. Since the insulating washer 33 is adjacent the support or frame 30, the stud 21 is amply insulated from the frame.

It will be noted, see Figs. 1 and 2, that the conical head 22 is of greater dimension than the opening 31. Therefore when the nut 35 is threaded on the end 21 to clamp the terminal assembly 26 to the support, the conical head will distribute the forces properly so that the insulated body will not be injured or fractured, thus short or open circuits are prevented. In case the nut 35 is run down on the threaded end 21 too far, clamping the terminal assembly 26 to the support, the conical design of the head 22 will distribute the forces in such a manner that the threaded end 21 will be severed or twisted in two.

without in any way injuring or fracturing the non-conducting material molded about the conical head 22. In this case, a new terminal would have to be supplied.

5 In Fig. 2 the terminal 26 is shown as connected by the wire 25, to the field windings of a generator within the frame 30, not shown. The outer end of the terminal 26 serves for attachment of a wire, not shown, by which the field winding is connected with other apparatus.

10 While the embodiment of the present invention as herein disclosed, constitutes a preferred form, it is to be understood that other forms might be adopted, all coming within the scope of 15 the claims which follow.

15 What is claimed is as follows:

1. A terminal assembly for a support having an opening, comprising in combination; a threaded shank having a head; a body of insulation about the head and shank and adapted to support the shank in the opening, said head comprising a flat portion surrounded by an outwardly flaring conic portion; and insulated means engaging the threaded shank for drawing the body 20 of insulation against the support, said flat head portion operating to draw the insulation about the shank into the aperture of the support and the flaring portion of the head adapted to clamp the insulation above it against the support.

20 2. A terminal assembly for a support having an opening, comprising in combination; a threaded shank having a head; a body of insulation about the head and shank and adapted to support the shank in the opening, said head comprising a flat portion surrounded by an outwardly flaring 25 conic portion; and insulated means engaging the threaded shank for drawing the body of insulation against the support, said flat portion operating to push the insulation resting thereon into 30 the aperture of the support and the flaring portion of the head adapted to angularly clamp the edge of the body against the support.

3. A terminal assembly for a support having a non-circular opening comprising, a threaded 35 stud having a head provided with a flat portion surrounded by an outwardly extending conical

portion; and a flanged insulating bushing attached to the stud, said bushing having a pilot portion adapted to register with the opening to prevent rotation of the bushing relative to the support and to entirely insulate the stud from the support; and insulated means for clamping the bushing against the support, said flat portion tending to push the pilot portion of the bushing into the opening and the conical portion operating at an angle to the axis of the stud 10 to clamp the flanged portion of the bushing against the support whereby the stud will be severed when the assembly is drawn too tight against the support.

4. A terminal assembly for a support having 15 an opening comprising in combination; a threaded shank having a head including a flat portion and a conic portion surrounding the flat portion; a body of insulating material, said body having a portion about the shank adapted to fit into the 20 opening and having a portion about the head adapted to engage the surface of the support about the opening; and insulated means for securing the assembly to the support whereby the flat portion of the head will push the insulation 25 parallel to the axis of the shank into the opening, and whereby the conic portion acts at an angle to the axis of the shank to clamp the edge of the body against the support.

5. A terminal assembly for a support having 30 an opening, comprising in combination; a threaded stud including a shank and a head, said head having a peripheral conic portion and a flat portion joining the conic portion with the shank; a body of insulating material molded about the 35 stud to enclose the conic portion and at least a portion of the shank, and insulated means for securing the assembly to the support whereby the flat portion of the head will force that portion of the insulating material about the shank 40 into the opening, and whereby the conic portion will distribute other portions at an angle to the axis of the shank to clamp edge of the body against the support.
